THE COLUMBIA PLANOGRAPH CO., WASHINGTON, D. C.

UNITED STATES PATENT OFFICE.

FRED D. WILLIAMS, OF OGDEN, UTAH.

BASS-DRUM AND CYMBAL BEATER.

1,309,082.

Specification of Letters Patent. Patented July 8, 1919.

Application filed January 27, 1917. Serial No. 144,921.

To all whom it may concern:

Be it known that I, FRED D. WILLIAMS, a citizen of the United States, residing at Ogden, in the county of Weber and State of Utah, have invented a new and useful Bass-Drum and Cymbal Beater, of which the following is a specification.

This invention relates to apparatus for use in beating bass drums and cymbals, one 10 of the objects of the invention being to provide an attachment which can be applied readily to a bass drum and which will hold the drum beater in such a position that the ball will strike the head of the drum at the center, the beater being so mounted as to act quickly on the rebound, thereby to insure accurate beating of the drum at any tempo.

A further object is to combine with the 20 drum beater an adjustable and reversible beater for use in connection with the cymbal, it being possible to use this cymbal beater so as to strike a cymbal located at either side of the drum or to entirely miss 25 the cymbal if preferred.

Another object is to provide a beater which can be collapsed into a compact bundle so as to be conveniently carried.

A still further object is to provide simple 30 and efficient means for properly holding in position a crash cymbal and also for holding the drum against shifting while in use.

With the foregoing and other objects in view which will appear as the description 35 proceeds, the invention resides in the combination and arrangement of parts and in the details of construction hereinafter described and claimed, it being understood that changes in the precise embodiment of the invention herein disclosed, can be made 40 within the scope of what is claimed, without departing from the spirit of the invention.

In the accompanying drawings the preferred form of the invention has been shown.

45 In said drawings:—

Figure 1 is a side elevation of the beating apparatus constituting the present invention, a portion of the counter hoop being shown in section.

Fig. 2 is a front elevation of the apparatus.

Fig. 3 is an enlarged section through the bearing of the drum beater.

Fig. 4 is a perspective view of one of the drum holding spurs.

Fig. 5 is a perspective view of the cymbal holder.

Fig. 6 is a perspective view of the holder used in connection with the crash cymbal.

Referring to the figures by characters of reference 1 designates a bass drum to the counter hoop 2 of which are to be connected holding spurs, one of which has been illustrated in detail in Fig. 4. Each of these holding spurs includes a tubular member 3 having a hook 4 at one end and having a depending pointed element 5. Within the tubular member is slidably mounted a shank 6 having a hook 7 at one end, while its other end is screw threaded and is engaged by a long wing bolt 8. The hook 7 is adapted to be placed back of the flesh hoop while the hook 4 is adapted to be placed in engagement with the front edge of the counter hoop. The two hooks are then adjusted 75 toward each other by means of the wing bolt 8. The holding spurs are designed to be secured to opposite sides of the lowermost portion of the counter hoop so that the ends of the pointed members 5 will bite into the floor or other structure on which the drum is mounted, so as to hold the drum against shifting out of any position to which it may be set.

A device such as shown in Fig. 6 is 85 adapted to be secured to the flesh hoop and counter hoop near the top thereof for the purpose of supporting a crash cymbal. This device includes a tubular member 9 having a hook 10 at one end and also having a boss 11 on which is arranged a threaded stem 12 engaged by a wing nut 13. A stem 14 is slidably mounted in the member 9 and has a hook 15 at one end, while its other end is engaged by a thumb rod 16. 90 The hooks 10 and 15 are adapted to be placed in engagement with opposed edges of the flesh hoop and counter hoop and to tightly

engage the same, after which the crash cymbal is placed on the stem 12 and fastened thereto by the wing nut 13.

For the purpose of attaching a small cymbal to either side of the drum, an attachment such as illustrated in Fig. 5 is used. This attachment includes a tubular member 17 having a hook 18 at one end from which extends an arm 19. A threaded stem 20 extends at right angles from this arm and is provided with a wing nut 21. A stem 22 is slidably mounted within the member 17 and is provided at one end with a hook 23 while its other end is engaged by a thumb screw rod or bolt 24. The hooks 18 and 23 are adapted to be placed in engagement with opposite edges of the flesh hoop and counter hoop and to be tightened thereagainst by the thumb rod or bolt 24. The cymbal which has been indicated at 25 is to be placed in engagement with the stem 20 and to be fastened thereto by the wing nut 21. Obviously this cymbal 25 can be secured to either side portion of the drum as may be most convenient.

The means for beating the drum and the cymbal 25 has been shown in detail in Figs. 1, 2 and 3. The beater attachment includes a base plate 26 to one side of which is attached a standard 27 having a spindle 28 projecting laterally from the upper end thereof. On this spindle is mounted a hub 29 the ends of which are recessed as at 30 to provide seats for ball bearings 31 engaging cones 32 projecting into the recesses. The hub is fastened to the spindle by a nut 33 or the like, said nut being housed by a cap 34 which serves to exclude dust and dirt and also to prevent the lubricant from escaping from the bearing.

Projecting from the hub is an arm 36 having an eye 37 at its free end into which projects a set screw 38. A tubular stem 39 is adjustably mounted on the eye and is engaged by the set screw, while adjustably mounted in this tubular stem is a rod 40 adapted to be held against longitudinal movement by a set screw 41. The ball 42 of the beater is attached to this rod.

An eye screw 43 engages one end of the tubular stem 39 and carries a ring 44.

An arm 45 extends from the hub 29 and is engaged by one end of a coiled spring 46, the other end of this spring being attached 55 to a bolt 47 which is adjustably mounted in a stud 48 outstanding from the standard 27. A nut 49 engages the bolt and by means thereof said bolt can be adjusted longitudinally to vary the tension of the spring 46.

Adjustably mounted on the tubular stem 39 is an arm 50 adapted to be held in place by a set screw 51. This arm has a spring extension 51' on which is mounted a ball 52 constituting means for engaging the cymbal

25. Obviously the arm 50 with its extension 51' can be inverted and replaced on the stem 39 so to adapt it for use in connection with a cymbal mounted at the other side of the drum.

Extending from the base plate 26 is a rod 53 the outer end of which is bent laterally to form a pintle 54 engaging a heel plate 55. This pintle also engages one end of a pedal 56 the other end of which is adjustably connected by a strap 57 to the ring 44.

The upper surface of the plate 56 may be roughened or may be provided with a covering of felt or the like. Extending upwardly from the plate is a threaded stem 58 which extends loosely through a clamping plate 59 bearing at one end on the plate 26. A wing nut 60 is mounted on the stem 58 and can be turned in one direction to cause the clamping plate 59 to bind the counter hoop onto the base plate 26, thus to hold the bearing mechanism fixed relative to the drum head.

It has been found in practice that a beating apparatus such as herein described is advantageous because it permits the ball 42 to hit the drum head at the center and it also allows the cymbal to be placed at either side of the drum, as may be found most convenient. By adjusting the arm 50 upwardly along the stem 39 it can be caused to entirely miss the cymbal. By utilizing the ball bearings in the hub 29, a quick rebound of the beater will take place and no difficulty will be experienced in using the drum while music is being played at the fastest tempo. The various adjustments which can be made are of importance. For example, stem 39 can be adjusted longitudinally within the eye 37, thus to increase or diminish the force of the stroke and the rod 40 can be adjusted longitudinally within the stem 39 to adapt the beater to drums of various sizes. The tension of the spring 46 can be varied to suit the performer. When the apparatus is not in use it can be readily folded up into a small package which can be conveniently carried.

What is claimed is:—

1. An apparatus of the class described including a base plate, a standard thereon, a spring restrained beater mounted upon and adapted to swing relative to the standard, means co-operating with the base plate for gripping the counter hoop of a drum, a rod extending from one end of the base plate and having its outer end bent laterally to form a pintle, a heel plate pivotally mounted on the pintle, a pedal pivotally mounted on said pintle and overhanging the rod, and a connection between the pedal and the beater.

2. An apparatus of the class described in-

cluding a base plate, means coöperating therewith for gripping the counter hoop of a drum, a rod extending from the base plate and having one end bent laterally to form 5 a pintle, a heel plate pivotally mounted on the pintle, a pedal pivotally mounted on said pintle and normally overhanging the rod, said heel plate and pedal being adapted to fold together and onto the rod, a 10 standard on the base plate, a beater adjustable in the direction of its length and pivot-

ally and adjustably connected to the standard, a connection between the pedal and one end of the beater, and yielding means connecting the beater to the standard. 15

In testimony that I claim the foregoing as my own I have hereto affixed my signature in the presence of two witnesses.

FRED D. WILLIAMS.
